UNITED STATES PATENT OFFICE.

WILLIAM BINNS, OF BINGLEY, ENGLAND, ASSIGNOR OF ONE-HALF TO JOSEPH
DOWNING MANDER, OF BINGLEY, YORK, ENGLAND.

TEXTILE SPINNING AND TWISTING PROCESS.

Application filed December 21, 1921. Serial No. 523,860.

To all whom it may concern:

Be it known that I, WILLIAM BINNS, a subject of the King of Great Britain, residing at Bingley, in the county of York and 5 Kingdom of England, have invented certain new and useful Improvements in Textile Spinning and Twisting Processes, of which the following is a specification.

The present invention relates to an im- 10 proved process and apparatus for the spinning of textile fibres or the fine spinning of textile yarn or sliver of the type in which the yarn is spun by the action of centrifugal force against the interior of a rotating cyl- 15 inder.

According to the present invention, a tex- 20 tile yarn or sliver unspun or partially spun and twisted is passed by means of an air current to the spinning place in contradis- 25 tinction to the rigid guides hitherto pro- posed for the purpose. It is preferably passed down a tube co-axial with it, rotating at a high speed of revolution preferably from 20,000 to 60,000 revolutions per min- 30 ute; the purpose of this tube is to impart some degree of twist to the yarn at the commencement of a spinning operation and so allow the machine to function automatically immediately it is started without any "piec- 35 ing up" or hand threading of the fibre being necessary.

This invention is more particularly de- 40 scribed with reference to the accompanying drawings in which:—

Figure 1 is a sectional side elevation showing one such arrangement.

Figure 2 is a sectional side elevation in large scale of a doffing device co-operating with the arrangement of Figure 1.

Figure 3 shows a modified form of doffing device.

Figure 4 is a detail being a sectional view on the line 4—4 of Figure 1.

Figures 5 and 6 show sectional elevations 45 and plan views respectively of the driving mechanism.

A textile yarn spun or partially spun and twisted is passed from a cop diagrammatically shown at 1, within a container 2, hav- 50 ing an air inlet 3. These parts are however not forming any part of the present invention and are shown purely diagrammatically.

The sliver or end to be spun passes be- 55 tween a series of slatted or slotted drawing rollers 4, 5, 6. In the arrangement shown these rollers rotate about their own axes but they may also rotate about the normal axis line of the fibre or sliver. The sliver is automatically passed down through a co-axial 60 tube 7, by means of an air current passing down said tube. The distance between the drawing rollers 5, 6, is preferably substantially equal to or less than the normal staple length of the yarn which is found to be an 65 essential condition for high speed spinning by the present process.

The end of the yarn passes into a tube 9, coaxial with the tube 7, and forming an extension thereof which however is provided 70 with driving teeth 10 meshing with teeth 11, on a driving wheel 12, which preferably, as shown in Figs. 5 and 6, drives a number of spindles, for instance four, equally spaced around it. The toothing 10, 11 is preferably 75 doubled helical toothing.

The yarn is spun by the action of centrifugal force as the end 13, leaves the tube 9 and becomes coiled in the form of a hollow cop on the interior of the cap 14, which may 80 be raised and lowered relatively to the end of the tube 9, following any desired known cop spinning method, and which preferably rotates at the same speed as the tube.

Owing to the distance between the spin- 85 ning point and the drawing rollers the unsupported fibre would break if inertia and a certain degree of twist were not applied to it by the rotation of the tube 9.

When however, it is desired to doff the 90 spun cop from the interior of the cap 14, a cop tube or spindle is inserted axially with the guide tube 9, the cap 14 stopped or slowed down relatively to the tube 9, when it will be found that on continued rotation 95 of the cop tube or spindle the cop of yarn will contract and become engaged by the said spindle or cop tube.

This doffing may be assisted by the feed- 100 ing in of compressed air at the top of the cap 14, or by an arrangement for instance as shown in Fig. 3, in which a cop tube 15, is used for doffing which is hollow and is connected with a supply of compressed air from an air trunk 16, which emerges from 105 holes 17, in the top of the tube above the

spun cop in the cap 14. This compressed air acts to blow down the spun cop on to the interior cop tube.

A plug 18 is preferably provided at the 5 top of this cop tube to engage with the end of the guide 9 to be driven by it.

A doffing arrangement is more particularly shown with reference to Fig. 2 in which the tube 9, is arranged to recede upwards 10 when it is desired to doff and an internal spindle 19 on a bracket 20 which can be lifted or lowered as desired from a pulley 21, has a splayed end 22, forming a driving clutch so that this spindle will be rotated 15 at the same speed as the tube 9.

After the clutching of these parts together the hollow cop tube 23, may be raised by operation of the pulley 24, which is intermittently rotated in opposite directions by a 20 transverse mechanism of well known type, which forms no part of the present invention and therefore is not illustrated until the tube lies within the hollow cop of yarn 25, when the outer cap 26, is slowed down 25 by interrupting the driving connection or by means of a brake or otherwise, when it will be found that if the rotation of the spindle 19, which engages by means of keys 27, with the hollow cop tube 23, is maintained, the hollow cop of yarn will automatically gradually shrink on to the cop tube 23 and become detached from the guide when it can be lowered into the position 30 shown in Fig. 2, whereupon then the spindle 19, can be lowered and the cop tube 23, doffed and replaced by a fresh tube or bobbin as desired.

It has been found that certain mechanical features of the drive for the various parts 40 are of importance. For instance it is preferred that the driven pinion should be less than $\frac{1}{2}$ inch pitch diameter and that the

tooth should have a rounded top with a 29° straight side and a root clearance, the pinion teeth preferably double or single helical.

45

The parts are preferably mounted throughout on ball or roller bearings automatically lubricated so that a high speed can be obtained without vibration or expenditure of unnecessary energy.

50

I declare that what I claim is:—

1. A textile spinning process comprising drawing a fibre sliver by rollers, leading said fibre sliver by means of an air stream down a coaxial tube and projecting it by centrifugal force within a hollow rotating cap.

55

2. A textile spinning process comprising drawing a fibre sliver by rollers, leading said fibre sliver by means of an air stream down a coaxial tube projecting it by centrifugal force within a hollow rotating cap and imparting relative axial motion between the end of the tube and the cap to obtain a traverse.

60

3. A textile spinning process comprising drawing a fibre sliver by rollers, leading said fibre sliver by means of an air stream down a coaxial tube projecting it by centrifugal force within a hollow rotating cap, imparting relative axial motion between the 70 end of the tube and the cap to obtain a traverse, inserting a cop axially with the tube when it is desired to doff and slowing down the cap to allow the spun fibre within it to contract on to said cop.

75

In witness whereof, I have hereunto signed my name this 7th day of December 1921, in the presence of two subscribing witnesses.

WILLIAM BINNS.
